DYEING APPARATUS

Henry E. Van Ness, Elmira, N. Y.

Application September 15, 1925, Serial No. 56,420. Renewed July 28, 1931

18 Claims. (Cl. 8—13)

This invention relates to apparatus for impregnating parts of an absorbent mass with a liquid, and more particularly to apparatus for spotting yarn by dyeing portions of a wound mass of the yarn.

Machines for carrying out the method of dyeing masses of yarn or other absorbent material, by injecting limited quantities of dye into predetermined portions thereof, are described and claimed in my co-pending applications Serial No. 629,633, filed April 3, 1923, and Serial No. 645,488, filed June 15, 1923. The present invention aims to provide an automatic machine for carrying out this method to eliminate all uncertainty attendant upon manual operation and to reduce the labor cost of yarn spotting. Specific objects of the invention are to provide in a machine for dyeing an absorbent mass, means for making simultaneous injections of dye at a plurality of points of the mass under equal pressures, means for adjusting the pressure under which the dye is injected, means for supplying dye automatically when the mass is in position to be dyed, automatic means for indexing or successively setting different portions of the mass in position to be dyed, and automatic means for stopping the machine when the dyeing of a predetermined part of the mass has been completed.

The nature of the invention, and the means by which I obtain these and other objects of the invention, may best be understood from a detailed description of a practical yarn dyeing machine embodying the invention. Such a machine is illustrated in the accompanying drawings, in which:—

Fig. 1 is a plan view of the machine;

Fig. 2 is an enlarged sectional elevation taken on the section line 2—2 of Fig. 1;

Fig. 3 is an enlarged section showing the clutch mechanism for the pump taken on the section line 3—3 of Fig. 2;

Fig. 4 is a sectional enlargement of the pump clutch and its component parts taken on the sectional line 4—4 of Fig. 3;

Fig. 5 is an enlarged sectional view of the brake band acting upon the crank shaft for preventing rotation of the same due to centrifugal force, taken on the section line 5—5 of Fig. 2;

Fig. 6 is a sectional view of the gearing arrangement for the machine taken on the section line 6—6 of Fig. 2;

Fig. 7 is an enlarged view showing the manner in which a bottle of dye is placed in inverted position at the top of the tank or reservoir;

Fig. 8 is a side view of the pump cylinder

and the enlarged portion or boss thereof with apertures for the attachment of injectors;

Fig. 9 is a sectional view taken on the line 9—9 of Fig. 2 showing the relation of the pump, valve stem, and injectors to each other; 60

Fig. 10 is a sectional enlargement of one of the injectors and its component parts taken on the section line 10—10 of Fig. 9;

Fig. 11 is a detailed view of the chuck for holding an injector needle; 65

Fig. 12 is a view of a cone of yarn having the injector needles inserted therein for dyeing a pattern in the mass;

Fig. 13 is a sectional enlargement of the work-holder and cone support taken on the section line 13—13 of Fig. 1; 70

Fig. 14 is an enlarged section taken on section line 14—14 of Fig. 2 showing the parts of the work-holder actuating mechanism;

Fig. 15 is an enlarged section showing the work support clutch mechanism taken on the section line 15—15 of Fig. 2; 75

Fig. 16 is a sectional enlargement of the work-holder clutch and the clutch-holding mechanism therefor taken on the section line 16—16 of Fig. 15; 80

Fig. 17 is a sectional plan view taken on section line 17—17 of Fig. 2 showing the mechanism for imparting rotary movement to the cone support; 85

Fig. 18 is an enlarged sectional view of the mechanism for operating the clutch-holder, taken on the section line 18—18 of Fig. 14; and

Fig. 19 is an enlarged sectional view of the clutch-holding mechanism for the work-holder clutch, taken on the section line 19—19 of Fig. 17. 90

The yarn spotting machine illustrated in the drawings has a frame comprising a plate B supported on legs B1 and B2. On the plate are mounted a pump P, having a dye reservoir T connected therewith, and a work-holder W. Under the plate B is suspended the driving mechanism which includes a main driving shaft S (on one end of which is mounted the continuously driven pulley P32), a crank shaft P23 for the pump P, which may be connected with the driving shaft through gears P34 and P35, a clutch P33, and a cam wheel W25 for operating the work-holder W which is mounted in alignment with the crank shaft P23 but is independently driven from the main shaft. During the operation of the machine a cone C of yarn is supported on the work-holder W and is moved thereby so as to bring successive portions of its surface adjacent to a bank of injectors J mounted on one side of the casing of the pump P. As successive portions of 100

95

100

105

110

the surface of the cone C are brought into operative relation with the injectors, the pump P is automatically operated to withdraw dye from the reservoir T and force it into the cone through the injectors. A curved plate A hinged to the plate B serves as a guard for enclosing the driving mechanism.

The pump P has a vertical cylinder P1 whose bore P5 is closed at its upper end by a cylinder head P3. In the lower end of the bore is a piston P22 which is reciprocated on rotation of the crank shaft P23 by means of a crank P10 and a connecting rod P24. Leakage around the piston is prevented by a packing ring P60. The inlet opening P8 of the pump is located slightly below the upper end of the pump cylinder and is connected with the dye reservoir T by means of a conduit P6 containing a ball check valve P7 to prevent the return of dye to the tank through this conduit. The pump outlet is controlled by the slide valve members P20 and P21 mounted on a valve stem P25 located in projection P66 at one side of the pump cylinder. The valve stem P25 is reciprocated by means of an eccentric P28 on crank shaft P23. Outlet openings P15 and P16 in the wall of the pump cylinder communicate through an intermediate vertical bore P13, the horizontal passages P17 and P18, and the vertical passages J13 with a bank of outlet openings P50 arranged in two vertical rows in the outer wall of the valve casing. Each opening is threaded for the insertion of an injector J (hereinafter described) or a plug J17. The passages P17 and P18 are normally closed by the valve members P20 and P21, but are simultaneously opened when the cut out portions P26 and P27 in the valve stem register with them.

It is apparent that on each down stroke of the piston P22 the pump cylinder will be filled with dye from the reservoir T up to the level of the top of the intake opening P8, and that on the up or compression stroke of the piston the dye in the cylinder and the air trapped in the upper portion of the cylinder will be placed under pressure and forcibly delivered to the injectors J in the outlet openings P50 when the valves P20 and P21 open the passages P17 and P18. The eccentric P28 is so positioned with respect to the crank P10 that the pump outlets are opened during the latter part of the compression stroke of the piston.

In order that the quantity of dye ejected from the pump on each compression stroke may be varied, the valve stem P25 is connected with the eccentric strap surrounding the eccentric P28 by means of a turn-buckle P29. The adjustment of this turn-buckle determines the exact point in the compression stroke of the piston at which the slide valves will open. The setting of the turn-buckle is indicated by a pointer P30 secured to the slide valve on a scale P31 on the slide valve casing.

In order that the pressure under which the dye is supplied to the injectors may be varied, the pump cylinder is connected to the dye tank T by means of a by-pass or a relief conduit P44 containing an adjustable valve P41. As the pump is mechanically driven so that each compression stroke of the piston is made at the same speed, the pressure which will be obtained in the pump cylinder at each compression stroke is determined by the setting of the valve P41. Since the passages P17 and P18 are simultaneously opened by the slide valves P20 and P21, the pressure developed in the cylinder is simultaneously

applied to all the outlet openings and to all the injectors J which may be mounted therein.

In order that the pump may be automatically operated whenever the cone of yarn C is in position to be dyed, the pump crank shaft P23 is connected to the gear P35 continuously driven by the gear P34 on the drive shaft S by means of the clutch P33 which causes the crank shaft P23 to make one complete revolution on each raising of the controlling rod P37 of the clutch. The clutch is of the type commonly used in punching machines and is therefore not described herein in detail. It is so set that it releases the crank shaft P23 on each revolution when the crank P10 and piston P22 are at their lowest points. Consequently, whenever the controlling lever P37 is raised, the pump makes one complete compression stroke, one complete intake stroke, and then stops.

To facilitate changing the dye used in the machine and to prevent liquid from standing in the machine when it is not in use, a valve controlled drain-pipe P47, communicating with the bottom of the bore P13, is provided. Through this pipe any liquid which, after the use of the machine, remains in the pump cylinder bore P5, in the passages connecting this bore with the injectors, or in the tank T, may be drained out.

The dye reservoir T is provided with a cushion ring T2 for supporting a bottle of dye in inverted position and providing a liquid seal for retaining the dye in the bottle and maintaining a constant dye level in the reservoir T. Besides facilitating the changing of the dye, this arrangement has the advantage of keeping the ingredients of the dye well mixed as the dye in the bottle is agitated by the bubbles of air which pass up into it whenever dye is drawn from the tank T.

The injectors J, of which any desired number may be inserted in the apertures or outlet openings P50, may consist merely of nozzles, that is, devices providing openings through which liquid may be discharged in a predetermined direction. The specific injectors shown in the drawings contain in addition to such nozzles, means for opening narrow passages into the mass of yarn.

As shown in the drawings, each injector comprises a nozzle J1 and a needle J2 fixed in the discharge opening of the nozzle. The nozzle J1 has a body J3, on the rear end of which is a threaded stem J4 which is screwed into one of the apertures P50. The body J3 contains an axial bore J5, which is the intake opening of the nozzle, and is also provided with a flanged portion J6 adapted to seat against the side of the projection P66 of cylinder P1. The outer portion of axial bore J5 is enlarged to receive the chuck J7 containing an axial bore J8 which forms the discharge opening of the nozzle. The chuck J7 is held in place by a nut J9 screwed on the front end of the body and engaging the chuck in such manner as to force the conical part J10 against a conical seat in the body. The outer end of the chuck is tapered so that when the needle J2 is inserted into a mass of yarn that portion of the chuck will also be introduced into the mass to prevent the injected liquid from spreading over the surface of the mass. In operative position the outer face or flanged end of nut J9 rests firmly against the surface of the yarn to further prevent undesirable spreading of the injected dye.

The needle J2 has its rear end inserted in the axial bore J3 of the chuck J7, being so retained by screwing the nut J9 inwardly to con-

tract the chuck. Since the shaft of the needle is of uniform diameter it may be gripped at any point by the chuck. Consequently the distance which the needle projects beyond the nut 5 J9 may be adjusted to allow for the desired penetration of the needle into an absorbent mass.

The needle J2 terminates in a point J11, the apex of which is on the axis of the needle. Extending substantially the entire length of the 10 needle and communicating with the discharge opening J5 is an open longitudinal groove J12 which is adapted to permit lateral egress therefrom throughout substantially the entire length of the portion of the needle projecting beyond the end J8 of the chuck J7. By varying the 15 arrangement of the injectors and the plugs J17 in the apertures P50, the needles J2 are caused to be inserted in different portions of the cone of yarn, as shown in Figs. 12 and 13.

The mass of absorbent material to be dyed is supported in such manner that the injector needles J2 will enter the mass substantially simultaneously and to the same depth, so that all the parts of the mass with which the needles 20 are in contact will be operated upon at the same time and in the same manner. This mode of operation coupled with the fact that the dye is forced through all the injector needles simultaneously under the same pressure assures uniformity of result. The mass of absorbent material to be dyed, whether yarn or otherwise, may have any convenient form, but is herein shown as a wound mass of yarn of frustro-conical form, indicated at C, and conventionally termed a 25 "cone of yarn."

The cone of yarn C is supported on a cone-shaped form or mandrel W3 mounted on an upright shaft W1 positioned equidistant from the two vertical rows of injector needles. The shaft 40 W1 is inclined toward the injector needles so as to present the yarn surface C1 perpendicularly to them. As a result of this arrangement the vertical rows of injector needles are equidistant from the points on the yarn surface C1 corresponding to or opposite them, thus assuring simultaneous penetration of the yarn mass by the injector needles. The mandrel W3 is provided near its bottom with a roughened surface W4 which serves to grip the core on which the yarn is wound to prevent rotation of the core about the mandrel. The upper portion of the mandrel is covered by a wooden form which is held in place by a screw W5. The mandrel 45 is detachably secured to the shaft W1 by means of a set screw W6.

The mandrel W3 which constitutes the yarn support or work holder is mounted to move toward and from the pump to bring the cone of yarn C into and out of operative relation with the injector needles J2. When the cone of yarn is in operative relation with the injector needles, the latter are received in the yarn mass as far as the flanged ends of the nuts J9. With the cone of 50 yarn and the injector needles in this relative position, the pump F is actuated to force the dye through the needles into the yarn mass, as shown in Figs. 12 and 13. The mandrel or yarn support is also mounted to cause the surface C1 of the cone of yarn which is toward the injector needles to move transversely of the needles so that a fresh portion of the yarn mass may be positioned opposite the needles. In order that the yarn surface C1 may be moved transversely of the axes of the injector needles J2, the shaft W1 which supports

the mandrel W3 and the cone of yarn is rotatably mounted in the inclined bearing W2 formed in the standard W7.

The yarn support W3 is moved into and out of operative relation with the injector needles by means of the cam wheel W25 which is loosely mounted on one end of the shaft P23 and on a stud W9 extending inwardly from one of the legs B2. In the periphery of the cam W25 is a groove W14 in which travels a roller W13 mounted on a stud W12 depending from the under side of a carriage W8 on which the standard W7 is supported and to which it is adjustably secured by the cap screws W69. The carriage W8 is slidably mounted on the plate B and is guided in its in-and-out movements relatively to the injectors by the guides W11 rising from the plate B. The cam groove W14 is of such shape that as the cam wheel W25 makes one complete rotation, the cone of yarn is moved into contact with the injector needles and withdrawn therefrom. When the cone of yarn has been moved into contact with the injector needles, it is held in that position to permit the dye to be injected into the yarn mass. For this purpose the cam groove W14 is 100 provided with a dwell W10 which extends around substantially one-quarter of the periphery of the cam wheel W25.

The cam wheel W25 is driven from the main shaft S:—a pinion W43 fixed on the shaft S meshes with a gear W49 connected with a clutch W43 mounted on a shaft W52 journaled in brackets depending from the plate B. On one end of the shaft W52 is fixed a pinion W44 which drives a gear W45 secured to the inner end of the cam 105 wheel W25. The clutch W43 is of the same construction and mode of operation as the clutch P33. When the clutch controlling rod W62 is raised the clutch W43 operates to communicate the rotation of the gear W49 through the shaft W52 to the cam wheel W25. The clutch W43 is manually closed at the beginning of the operation of the machine by means of the handle W51 fixed on the forward end of a rod W50 mounted transversely under the plate B. The rod W50 is 110 operatively connected with the clutch controlling rod W62 through the arms W27. To insure instantaneous stopping of the rotation of the shaft W52 when the clutch W43 is opened by the depression of the rod W62, a spring-pressed plunger W55 acts as a brake on the disk W56 fixed on the shaft W52. 115

While the dwell W10 of the cam groove W14 is in engagement with the roller W13 holding the cone of yarn in contact with the injector needles J2, the piston P22 is actuated to force the dye through the injector needles and into the yarn mass. For this purpose a cam surface W57 formed on one of the sides of the dwell groove W10 is adapted to engage with a roll W58 carried by the lower end of an arm W56 fixed on one end of a rod W59 journaled in the machine frame and extending longitudinally under the plate B. On the other end of the rod W59 is fixed an arm W60 pivotally connected by the link W46 and lever W48 with the clutch operating rod P37. The ratio of the gear connections between the shaft S and the crank shaft P23 and the gear connections between the shaft S and the cam wheel W25 is such that the crank shaft P23 makes four revolutions while the cam wheel W25 makes one revolution. Consequently when the clutch P33 is operated to connect the crank shaft P23 with the main shaft S by reason of the oscillation of the rod W59 through the engagement of the roller 120 125 130 135 140 145 150 155 160 165 170 175 180 185 190 195 200

W58 by the cam surface W57, the crank shaft P23 makes one complete revolution to actuate the piston P22 and the valve stem P25 while the dwell W10 of the cam groove W14 is in engagement 5 with the roller W13 holding the cone of yarn in contact with the injector needles.

The yarn support W3 is rotated or indexed to position fresh portions of the yarn surface opposite the injector needles by means of a ratchet 10 wheel W15 secured to the lower end of the inclined shaft W1 and resting on the inclined surface W29 which forms the bottom of a ratchet housing in the top of the standard W7. A cover W22 secured to the top of the standard W7 completes the housing in which the ratchet W15 is located. The ratchet W15 is actuated by means of a pawl W20 pivoted in the cutaway middle portion of a rod W19 slidably received in a sleeve W18 located on one side of the standard 15 W7. A leaf spring W21 secured to the rod W19 presses the pawl W20 into engagement with the teeth W41. A spring-pressed plunger W23 housed in the plate W22 acts as a brake on the ratchet W15.

25 When the carriage W8 is moved forward toward the pump P to bring the cone of yarn in contact with the injectors, the forward end of the rod W19 encounters an adjustable stop W26 threaded in the upper end of an upright W24 rising from the plate B. The engagement between the forward end of the rod W19 and the stop W26 arrests the forward movement of the rod W19 while the carriage W8 is completing its travel to bring the cone of yarn into full operative relation with the injector needles. This additional forward travel of the carriage W8 and the parts connected with it while the rod W19 is arrested causes the next succeeding tooth on the ratchet W15 to be brought into engagement 30 with the pawl W20. On the return movement of the carriage W8 and the parts connected with its rear end of the rod W19 encounters a stop screw W28 mounted in a bracket W27 secured to the end of the plate B. The rear end of the rod 35 W19 encounters the stop W28 before the carriage W8 completes its return travel from the pump. The further outward travel of the carriage W8 and the parts connected with it while the rod W19 is arrested causes the pawl W20 to turn the ratchet W15, whereby the cone of yarn 40 is indexed through an arc corresponding to the angular distance between the ratchet teeth W41. If it is desired to vary the circumferential distance between the spots to be dyed in the cone 45 of yarn, the number of ratchet teeth W41 will be varied accordingly.

When the machine is set in operation by turning the handle W15 in a clockwise direction to lift the rod W62 which controls the clutch W43, 50 the machine continues to run (unless manually interrupted as hereinafter explained) until the yarn dyeing operation is completed. To hold the clutch controlling rod W62 raised to maintain the machine in operation the upper end of the rod W62 is loosely connected with one end of a bar W53 pivotally mounted in the upright W54 rising from the plate B. The other end of the bar W53 is adapted to be held depressed, to keep the rod W62 raised, by the lower end of a lever 55 W30 pivoted in the upright standards W32. The compression spring W33 acting on the upper end of the lever W30 tends to force the lower end thereof toward the bar W53. A handle W31 secured to the upper end of the lever W30 provides means whereby the bar W53 may be re-

leased to stop the machine at any desired point in its cycle of operations.

The bar W53 is automatically released to stop the machine, when the dyeing operation of the whole cone has been completed, by the engagement of a block W38 with the plate W34 secured to the upper end of the lever W30 while the cone of yarn is being retracted on the completion of the dyeing operation. The block W38 is pivotally mounted on the outer end of a rod W36 80 slidingly supported in a sleeve W35 mounted on the plate W22. A leaf spring W39 yieldingly holds the block W38 in its normal position. On the inner end of the rod W36 is a bevel faced block W37 which is spring pressed into the path 85 of rotation of the bevel face pin W17 projecting radially from a collar W16 fixed on the shaft W1 and resting on the center of the ratchet wheel W15. A pin W41 projecting upwardly from the rod W36 travels in the slot W42 in the sleeve 90 W35 and thereby prevents the rod W36 and the blocks W37 and W38 from turning.

When the cone of yarn to be dyed is placed on the yarn support the radial pin W17 occupies a position immediately beyond the block W37, that 100 is to say, immediately to the left of the block W37, viewing Fig. 1. The yarn support rotates in a counter clockwise direction so that when the last undyed portion of the cone of yarn is opposite the injector needles the bevelled face of 105 the pin W17 is in contact with the bevelled face of the block W37, thereby holding the block W38 in position to strike the outer curved end of the plate W34 as the yarn support moves toward the injector needles. When the bevelled face 110 of the block W38 strikes the plate W34 the spring W39 yields and permits the bevelled face of the block W38 to travel past and in contact with the plate W34 without actuating the lever W30. As the yarn support completes its inward move- 115 ment towards the injector needles the block W38 passes beyond the inner end of the plate W34. The spring W39 thereupon restores the block W38 to its normal position. Then as the yarn support is retracted after the dyeing operation, 120 the straight face of the block W38 encounters the inner curved end of the plate W34 and forces it and the upper end of the lever W30 outwardly 125 against the action of the spring W33, thereby disengaging the lower end of the lever W30 from the bar W53 and permitting the spring W47 to depress the clutch controlling rod W62 and stop the machine.

The mode of operation of the improved yarn 130 spotting machine may be briefly recapitulated as follows:—The desired arrangement of the injector needles J2 is effected by inserting the needles in the appropriate apertures P50. The unoccupied apertures are then closed by the plugs J17. The pressure under which the dye is to be 135 forced through the injector needles into the yarn mass is controlled by regulating the valve P41 in the by-pass P44. The quantity of dye to be injected through the needles into the yarn mass is determined by the position of the openings P26 and P27 in the valve stem P25 relatively to the piston P22. The positions of these various parts having been determined experimentally the cone of yarn C to be dyed is placed on the yarn support W3, the straight face of pin 140 W17 resting against the straight face of block W37, as shown in Fig. 1. The operator then starts the machine by turning the handle W51 in a clockwise direction to lift the clutch controlling rod W62 to permit the clutch W43 to 145 150

connect the constantly rotating gear W49 with the cam wheel W25. The upward movement of the rod W62 depresses the outer end of the bar W53 so that the spring W33 may force the lower end of the lever W30 into engagement therewith to hold the rod W62 raised throughout the yarn dyeing operation. The rotation of the cam wheel W25 causes the carriage W8 and the cone of yarn mounted thereon to be moved toward and retracted from the injector needles J2. While the dwell W10 of the cam groove W14 is in engagement with the roller W13 the cone of yarn is held in operative relation with the injector needles to permit the dye to be injected into the yarn mass. During the time that the roller W13 is in the dwell part W10 of the cam groove W14 the cam surface W57 connected therewith moves into engagement with the roll W58 to oscillate the rod W59 to operate the clutch P33 and there-
20 by set in operation the crank shaft P23 to actuate the piston P22 and the valve stem P25. As the carriage W8 completes its in-and-out movement toward and from the injector needles, the sliding rod W19 causes the pawl W20 to turn the cone of yarn by its operative engagement with the teeth W41 of the ratchet wheel W15. By the time that the last undyed portion of the cone of yarn has been positioned opposite the injector needles the radial pin W17 has moved into engagement with the block W37 thereby moving and holding the block W38 in position to engage with the plate W34. On this forward movement of the cone of yarn the block W38 slides over the plate W34 inoperatively. As the cone of yarn is retracted from the injector needles for the last time the straight side of the block W38 encounters the inner end of the plate W34, and forces it and the upper end of the lever W30 outwardly, thereby disengaging the lower end of the lever from the outer end of the bar W53 and permitting the spring W47 to depress the clutch controlling rod W62 and stop the machine.

It is to be understood that the present invention is capable of modification and accordingly is not to be limited by the illustrated embodiment but only by such structures as are defined by the appended claims.

What is claimed is:

1. In apparatus of the class described, a support for a cone of yarn, and two spaced parallel nozzles directed toward a cone mounted on the support with their axes at opposite sides of the axis of such a cone.

2. In apparatus of the class described, the combination of two rows of parallel injectors arranged with their axes in parallel planes, and means for supporting the cone of yarn with its axis transverse to the axes of the injectors and in a plane midway between said parallel planes.

3. In apparatus of the class described, two rows of parallel injectors with their axes in parallel planes, a support for said injectors, and a work-holder adapted to hold a cone of yarn with its axis transverse to the axes of said injectors and in a plane midway between said parallel planes, said work holder and said support being mounted for relative approaching and separating movements in a direction parallel to the axes of the injectors and parallel to said planes.

4. In apparatus of the class described, the combination of a pump having a cylinder, a piston and a discharge opening, a support for an absorbent mass, means for placing different numbers of injectors in communication with said

discharge opening for directing liquid into said mass, a valve controlling the discharge opening of the pump, and means for varying the time of the opening of said valve with respect to the compression stroke of the piston to vary the amount of dye ejected by the pump.

5. In apparatus of the class described, a pump having a reciprocating piston and a reciprocating outlet valve, a shaft for reciprocating said piston and valve, means for intermittently rotating said shaft arranged to release it at the same point in its revolution after each actuation thereof, adjustable means connecting the valve with the shaft to permit a variation of the point of opening of the valve with respect to the compression stroke of the piston, an indicator carried by the valve, and a fixed scale on which the position of said indicator is readable when said shaft is released.

6. In apparatus of the class described, a dye tank, a pump having a compression chamber and a mechanically operated piston, an intake conduit from the tank to the compression chamber, a check valve to prevent return flow therethrough, means for directing liquid placed under pressure in said chamber into an absorbent mass, a by-pass conduit from the compression chamber to the tank, and an adjustable constriction in said by-pass for varying the pressure developed in the compression chamber.

7. In apparatus of the class described, the combination with a pump having a cylinder with intake and discharge openings and a mechanically operated piston in said cylinder and a valve controlling the discharge opening, of a dye tank, an intake conduit from the dye tank to the intake opening of the cylinder, a check valve to prevent the return flow therethrough, means communicating with the discharge opening of the cylinder to direct liquid into an absorbent mass, means for opening the discharge valve at a predetermined point in the compression stroke of the piston, a by-pass from the cylinder to the tank, and an adjustable constriction in said by-pass for varying the pressure developed in the compression chamber at the time of the opening of the discharge valve.

8. In apparatus of the class described, the combination with an injector and a support for an absorbent mass, of means for causing relative motion between them to bring different parts of the mass successively into operative relation with the injector, and means automatically actuated by said moving means to operate the injector when each successive portion of the mass is in operative relation to it.

9. Apparatus of the class described, comprising a nozzle, a support for an absorbent mass, and automatic means for causing relative approaching and separating movements between the support and the nozzle and for stopping each approaching movement when the surface of the mass is pressed firmly against the end of the nozzle.

10. In apparatus of the class described, the combination of an injector and a support for an absorbent mass, means for causing relative approaching and separating movements thereof in a direction parallel to the axis of the injector, means automatically actuated by said means to cause operation of the injector at the end of each approaching movement, and means automatically actuated by said moving means for causing a relative movement of the injector and

the surface of the mass in a direction transverse to the axis of the injector.

11. In apparatus of the class described, the combination of an injector and a work-holder, means for causing relative approaching and separating movements thereof, means actuated by said moving means to cause operation of the injector at the end of each approaching movement, and means automatically actuated by said moving means to turn the work-holder after each operation of the injector.

12. In apparatus of the class described, the combination of an injector and a work-holder adapted to hold a wound mass of yarn with its axis transverse to the axis of the injector, means for causing relative approaching and separating movements between the work-holder and the injector, means automatically operated on each cycle of such relative movement to cause a partial rotation of the mass about its axis, and means operable on one complete rotation of the mass to stop said relative approaching and separating movements.

13. In apparatus of the class described, the combination of an injector and a work-holder for holding a cone of yarn, means for causing relative approaching and separating movements between the work-holder and injector, means for causing a partial rotation of the cone on each cycle of such movement, and means operable on the completion of a rotation of the cone to stop said relative movement at the end of a separating movement.

14. In apparatus of the class described, the combination of an injector and a work-holder, means for causing relative approaching and separating movements of the injector and work-holder, a clutch connected with said moving means adapted when released to stop said relative movement at the end of a separating movement, and manual means for releasing said clutch.

15. In apparatus of the class described, the combination of a work-holder, an injector, a pump for forcing liquid through said injector, means for causing relative approaching and separating movements between the work-holder and

the injector with a dwell at the end of each approaching movement, and automatic means for causing a compression stroke of the pump during each such dwell.

16. In apparatus of the class described, the combination of a work-holder, an injector, a pump for forcing liquid through said injector, means for driving the pump, a clutch connecting the driving means with the pump and arranged when closed to cause a single operation of the pump, a rotary member arranged to cause a relative approaching and separating movement between the work holder and the injector on each rotation thereof, and a projection on said rotary member positioned to close the pump clutch at the end of each such approaching movement.

17. Apparatus of the class described, comprising a fixed injector, a carriage mounted for reciprocatory movement parallel to the axis of the injector, a mandrel rotatably mounted on said carriage with its axis transverse to that of the injector, a wheel on said mandrel, a pawl, a pawl holder movably mounted on the carriage, engaging members positioned to reciprocate the pawl holder with respect to the carriage on each reciprocatory movement of the carriage, and means for adjusting the position of said engaging members to vary the stroke of the pawl holder.

18. Means for automatically dyeing an absorbent mass of material according to a prearranged pattern including a support for said material, a dye reservoir, means for simultaneously injecting dye into said material at spaced points, means for mounting said injecting means according to a prearranged pattern, means for withdrawing dye from said reservoir and simultaneously supplying measured quantities thereof under uniform pressure to said injecting means, means for automatically indexing the material between injections of dye therein, and means for stopping the injecting and indexing means when the pattern is completed, whereby the dye spreads uniformly from each point of the pattern substantially without overlap or intermixture.

HENRY E. VAN NESS.
